UNITED STATES PATENT OFFICE

157,704

CHILD'S SLIPPER OR SIMILAR ARTICLE

Henri E. Rosen, Brookline, Mass.

Application April 21, 1949, Serial No. 2,177

Term of patent 7 years

(Cl. D7—7)

To all whom it may concern:

Be it known that I, Henri E. Rosen, a citizen of the United States, residing at Brookline, in the county of Norfolk and Commonwealth of Massachusetts, have invented a new, original, and ornamental Design for a Child's Slipper or Similar Article, of which the following is a specification, reference being had to the accompanying drawing, forming part thereof.

Fig. 1 is a side elevation of a child's slipper, showing my new design;

Fig. 2 is a plan view of the same;

Fig. 3 is a front elevation of the same; and

Fig. 4 is a bottom view of the same.

The essential features of my design reside in the specific configuration of the animal-like head appearing on the vamp portion of the shoe in combination with the cap on the right side thereof, all as illustrated.

I claim:

The ornamental design for a child's slipper or similar article, as shown and described.

HENRI E. ROSEN.
